UNITED STATES PATENT OFFICE

2,533,883

INVENTORY INDICATOR

Abe Gelb, New Rochelle, N. Y.

Application April 13, 1948, Serial No. 20,735

2 Claims. (Cl. 116—133)

1

The present invention relates to devices to show quantity of material wound on a board, reel or spool, or contained in a box, so that inventory of stock at hand may be readily ascertainable of each item.

An object of this invention is to provide a novel and improved device to show the length of material wound on a board, reel or spool, as for instance of bolts of cloth, fabrics, laces, ribbons, tapes, trimmings, ropes, belting or the like, or of the quantity of articles in a receptacle, as in a paper box or the like, which is manually set to a new reading each time any of the material is cut off or otherwise removed, and though roughly dealt with in handling, will not loosen to upset the reading.

A further object is to provide a novel and improved device of the character mentioned, which is securely attachable and easily detachable from the winding board, box or the like, or the merchandise itself, if such manner of use is necessary.

Another object hereof is to provide a device of the type mentioned, which is easy to use, simple in structure, cheap to manufacture and efficient in carrying out the purposes for which it is designed.

Other objects and advantages will become apparent as this disclosure proceeds.

Fig. 1 is a perspective view showing a device embodying the teachings of this invention, as used in connection with a board on which a substantial length of a lace or similar trimming, is wound.

Fig. 2 is an enlarged sectional view taken at lines 2—2 in Fig. 1, showing how the device securely attaches itself to the board, and yet is easily removable.

Fig. 3 shows the face of one of the number wheels included in said device.

Fig. 4 shows a development of the blank used to form the body component of the said device.

Fig. 5 is a sectional view similar to that of Fig. 2, but of a slightly modified form of body component for said device.

Fig. 6 shows a development of the blank used to form such modified body structure.

In the drawings, the device indicated generally by the numeral 15, is used to show the quality, as for instance the length of lace 16, wound on board 17. Said device comprises a body member formed of sheet material on which are rotatably mounted a plurality of coplanar number wheels or discs 19, 20 and 21, the perimetral edges of which are preferably serrated, as at 22. The

2

body member 18 is preferably made of springy material, as metal or plastic sheeting, and its blank 18' may be rectangular, folded in half to form a U-clamp for the board 17. The edges of the plies of said body member 18, may be folded inwardly as at 23 and 24, or in any other suitable manner to afford smooth entrance of the board 17 between the plies of the body member 18. Said body member is provided with slots 25, 26 and 27, which serve as windows for viewing a numeral of a series printed on each of the number discs 19, 20 and 21. All of the number wheels are mounted on individual eyelets or the like on one of the plies of the body member, while the other ply is formed with projections or teats 28 and 29, which when the device is mounted on the board 17, will enter respectively holes as for instance 30 and 31, which are through the board 17, one set of such holes at each longitudinal edge thereof, so that the device may be mounted on said board at predetermined positions. In the blank 18', note the slots 32, 33 and 34, through which segments of the respective number discs may project to be accessible for manual manipulation. The notations on one of said number wheels may be a series of fractions, so that the yardage may be so indicated. The reading of the device in Fig. 1, indicates 27½ yards. It is also to be noted that when the device 15 is mounted on the board, said board lends friction against the number wheels 19, 20 and 21, so that their setting is not disturbed by ordinary handling of the lace and board.

The blank 18'' shown in Fig. 6, is for the modified form of body indicated generally by the numeral 38. Here the blank is bent to form a three-ply S-shaped item, where the number wheels lie between two of the plies, one of which is the middle ply, while said middle ply and the third ply of body member 38, serves as the clamp to receive the board 17. Teats, one of which is shown in Fig. 5, and indicated in the blank by the numerals 28' and 29' are included for the purpose hereinbefore described. All the cut outs in the blank 38, are marked the prime numbers of those they are akin to in Fig. 4. The plies of body member 38, between which the number wheels are mounted, are in frictional contact therewith, to maintain said wheels in any set positions.

The indicating device 15 though shown mounted on board 17 having lace, ribbon or in suitable dimension, cloth wound thereon, may be similarly mounted on the rim edge of a box containing merchandise or articles of various kinds, or may

be directly mounted on the cloth, or on the end of rope or chain, if such be the goods on which said device is to be used.

In use as shown in Fig. 1, the wheels 19, 20 and 21, are initially set to show the yardage of the material 16 on the board. If any is cut off, as when a quantity of said lace is sold, the number wheels are reset to show the yardage then remaining. Hence perpetual inventory is maintainable. The notation on the number wheels is of a nature suitable to the specific purpose for which said devices are employed, and such use will determine the number of number or other nomenclature wheels, the device shall have.

This invention is capable of numerous forms and various applications without departing from the essential features herein disclosed. It is therefore intended and desired that the embodiments herein shall be deemed illustrative and not restrictive and that the patent shall cover all patentable novelty herein set forth; reference being had to the following claims rather than to the specific description herein to indicate the scope of this invention.

I claim:

1. In a device of the character described, to be mounted on a board, comprising a body member of springy sheet material bent into at least a first ply and a second ply to form a U-clamp adapted to grip the board and at least one disc having numerical notations thereon, positioned

between the plies of said clamp, spaced from the first ply, flat against the second of said plies and rotatably mounted on the body member, whereupon insertion of said board between the plies of the clamp formed and between said disc and the first ply of the body member, said board will be gripped thereby and will frictionally contact said disc, holding same against accidental rotation with respect to the body member; one of the plies of the body member being provided with an opening through which indicia on the disc is exposed to view.

2. A device as defined in claim 1, wherein the board is provided with a socket and one of the plies forming the clamp is provided with a protuberance extending towards the other ply of said clamp, whereupon insertion of the board between the plies of the clamp, said board will be gripped thereby and the protuberance will enter the socket, whereby the plies of the clamp need be manually spread apart to release the board.

ABE GELB.
